US0D1087777S

(12) United States Design Patent (10) Patent No.: US D1,087,777 S
(45) Date of Patent:  Aug. 12, 2025

(54) DETERGENT BOTTLE

(71) Applicant: Guangdong Seaways Biotechnology Co., Ltd., Zhongshan (CN)

(72) Inventors: Hao Yin, Zhuhai (CN); Baoqiong He, Foshan (CN); Lanying Lai, Yingde (CN); Xiaojuan Hou, Kaifeng (CN); Jingwen Cui, Zhongshan (CN)

(73) Assignee: Guangdong Seaways Biotechnology Co., Ltd., Zhongshan (CN)

() Term: 15 Years

(21) Appl. No.: 29/993,567

(22) Filed: Mar. 14, 2025

(30) Foreign Application Priority Data

Nov. 14, 2024 (CN) 202430721804.5

(51) LOC (15) Cl. 09-01

(52) U.S. Cl.

USPC D9/539; D9/549
